DEODORANT DISPENSING DEVICE

Stephen J. Benn, Philadelphia, Pa.

Application November 17, 1943, Serial No. 510,676

2 Claims. (Cl. 4—227)

1

This invention relates to deodorizing or disinfecting means for use in conjunction with flush tank toilets.

The object of the invention is to provide a flush tank with means for dispensing a predetermined quantity of deodorant, incense, or disinfectant into the flush water upon actuating the flush valve in order to destroy or render innoxious any effluvia.

A further and particular object of the invention is to provide a device for the purpose mentioned which may be readily applied to the flush tank without any alteration or substitution of parts in the tank or its operative mechanism, and without necessitating the services of a mechanic.

A further object of the invention is to provide a device of the class mentioned which may be manufactured and supplied to the market as a complete operative unit adapted to be placed in position within the flush tank and coupled to flushing mechanism by a single simple operation.

Other objects will appear hereinafter.

With these objects in view, the invention consists generally in a container for a deodorant or disinfectant provided with means for suspending the same within a flush tank, a discharge opening in said container, a valve normally closing said opening, a valve actuating lever pivotally mounted on the container, a link attached to said lever and adapted to be connected to the flush valve release mechanism so that upon each actuation of the latter, said lever will operate the valve to permit a desired quantity of deodorant or disinfectant to be discharged into the flush water within the tank.

The invention will be more readily understood by reference to the accompanying drawing forming a part of this specification and in which:

Figure 1 is a plan view of a portion of a flush tank illustrating the device suspended therein, and

Figure 2 is a section on the line 2—2 of Fig. 1.

Referring now to the drawing, 5 indicates a flush tank of the usual type, and 6 and 7, portions of adjacent end and front walls thereof respectively. In the front wall of the tank is the usual bushing 8 within which is mounted a shaft 9 on the outer end of which is fixed the flush handle 10 for actuating the flush valve, not shown. The inner end of the shaft is usually polygonal in cross-section as indicated at 11, and upon this is mounted the hub 12 of the flush valve lifting arm or actuating lever 13. A screw or bolt 14 is tapped through the hub 12 to secure

2

the arm 13 to the shaft. These parts are old and form no part of the invention except in combination with the features hereinafter described.

A receptacle 15 is provided for the deodorant, incense or disinfectant, and may be of any desired shape or size. Formed in or secured to the receptacle are a pair of hangers 16, shaped to engage over the upper edge of the end wall 6 of the tank. These are of inverted U-shape and of sufficient length to support the receptacle the proper distance below the upper edge of the tank. The portion of the hangers immediately above the receptacle are offset as indicated at 17 to hold the receptacle in spaced relation to the adjacent wall 7 of the tank. This minimizes or prevents accumulation forming between the receptacle and the adjacent wall of the tank and also maintains the actuating mechanism hereinafter described from contacting the wall of the tank. In the top of the receptacle is a filling opening provided with a closure 18.

In order to discharge a portion of the contents of the receptacle upon each actuation of the flush handle, the receptacle is provided with a discharge opening controlled by a valve which is actuated by a trip arm suitably connected to the flush handle shaft. To this end the bottom of the receptacle is formed with a boss 19 into which is threaded a bushing 20 having a bore 21 constituting the discharge opening. The upper end of the bore is contracted and formed with a valve seat 22 for a poppet valve 23 having a stem 24 extending below the boss 19. Interposed between a shoulder formed by the contracted portion of the bore and a spider or guide 25 on the stem 24 is a spring 26 for normally holding the valve on the seat.

Mounted on the receptacle adjacent the lower portion thereof is a bell crank lever 27. This lever is preferably mounted on a stud 28 on a lug 29 depending from the bottom of the receptacle. This lever may be stamped from sheet metal, and comprises a substantially horizontal trip arm 30 extending under the receptacle and beneath the valve stem 24, and an upwardly extending arm 31 having a laterally offset lug 32 at its upper end which is perforated to receive one end of a tie rod 33, the opposite end of which rod is provided with a perforated end 34 through which the screw 14 is extended to attach the discharge medium of the receptacle to the flush handle. The end of the tie rod extending through the lug 32 is threaded as at 35 to receive nuts 36 which are arranged on opposite sides of the lug 33 and by means of which adjustment may be made between the lever

27 and the flush mechanism to properly position the arm 30 with relation to the valve stem 24. In order to facilitate the operation of the device with ease and without strain on the mechanism, the arm 31 is of sufficient length to extend an appreciable distance above the level of the shaft 9, and the rod 33 extends horizontally therefrom to adjacent said shaft and is then bent angularly downward as indicated at 37 to engage the screw 14 at right angles, or tangentially to its path of motion.

It should be noted that the entire device is of unitary construction, that is, it forms a complete operative unit which, as a whole, may be positioned and supported within the flush tank by merely slipping the hangers 16 over the upper edge of the end wall of the tank and coupling the tie rod 33 to the flush medium of the tank by simply removing the screw 14 and replacing the same after having extended it through the perforation in the end 34 of the tie rod. After the device is installed, should it be found that too little or too much fluid is being discharged from the reservoir upon actuation of the flush, the amount can be readily regulated by adjusting the nuts 36 on the tie rod. The operation of the device is believed to be clear from the drawing and the foregoing description.

I claim:

1. The combination of a flush tank provided with the usual flush valve actuating lever, with a reservoir suspended therein, said reservoir provided with a discharge opening in the lower portion thereof, a discharge valve normally closing said opening, a stem on said valve extending below the reservoir, a bell crank lever pivotally mounted on said reservoir, and comprising an arm extending beneath said valve stem and an arm angularly disposed with relation to the first said arm, and a connection between the last said arm and the flush valve actuating lever.

2. The combination of a flush tank provided with the usual flush valve actuating lever, with a reservoir suspended therein, said reservoir provided with a discharge opening in the lower portion thereof, a discharge valve normally closing said opening, a stem on said valve extending below the reservoir, a bell crank lever pivotally mounted on said reservoir, and comprising an arm disposed in generally horizontal position and extending under said valve stem and an uprightly disposed arm having a laterally projected lug, and a flexible thrust rod secured to and movable with the flush valve actuating lever and adjustably secured to said lug.

STEPHEN J. BENN.
